CRACKING PROCESS

Stewart P. Coleman, Houston, Tex., assignor to
Standard Oil Development Company, a corpora-
tion of Delaware

Application April 23, 1929. Serial No. 357,398

4 Claims. (Cl. 196—67)

This invention relates to the art of decom-
position or cracking of mineral oils by direct
contact with heated gases and it is a continua-
tion in part of my prior application Serial No.
5 310,255. The specific purpose of the present ap-
plication is to improve the process of the ap-
plication Serial No. 310,255 so as to make it
available for the treatment of very low grade
cracking stocks, such as topped asphalt base
10 crudes, low grade fuel oils, etc.

Briefly, the process consists of vaporizing the
heavy oil to be cracked, in contact with hot,
non-oxidizing gases, drawing off the unvapo-
rized heavy portion, introducing the gas and
15 vapor mixture into a cracking chamber where
they come in contact with a further quantity
of very hot, non-oxidizing gases. Preferably
higher than atmospheric pressure is maintained
in the apparatus during these operations. The
20 heavier hydrocarbons decompose into light hy-
drocarbons and are drawn off, cooled and sepa-
rated from the uncondensable gases.

The drawing is a semi-diagrammatic vertical
section of an apparatus for accomplishing this
25 improved process and clearly indicates the flow
of materials.

Referring to the drawing, reference character
1 designates a furnace or combustion chamber
heated with a burner 2 which may be fed either
30 by line 43 with gaseous fuel or by line 23 with
fuel oil. Since the process is operated under
higher than atmospheric pressure, the air is
supplied to the burner by compressor 3 and line
4. The combustion chamber 5 is lined with fire
35 brick 6 and may be filled with checker brick as
shown at 7 to effect the combustion in a short
time and in a comparatively small space. The
furnace 1 may be replaced by any other source
40 of hot, non-oxidizing gases such as a gas pro-
ducer the products of which consist mainly of
nitrogen, carbon monoxide, carbon dioxide and
water vapor. The source of hot non-oxidizing
gases will be termed gas generating zone in the
45 claims.

45 The combustion gases leave furnace 1 by the
flue 8 and after admixture with the proper
amount of steam supplied by line 9, are dis-
charged through the manifold 10 into the well
50 insulated cracking chamber 11. It is also feas-
ible to entirely eliminate the furnace (1) or the
gas producer and use highly super-heated steam
alone for admixture with the oil vapors to be
cracked.

The cracking stock is passed from the accum-
55 ularator 12 through line 12a, pump 13, heat ex-

changer 14, line 15 and is discharged through
the spray 16 into the vaporizing tower 17.
There are also discharged into the vaporiz-
ing tower hot, non-oxidizing gases through line
8'. These gases may be bypassed from line 8 60
through line 8a or may be obtained from a sepa-
rate source such as the furnace 1'. The num-
bers 1'—8', 23' 43' designate elements analog-
ous to 1—8, 23 and 43 respectively. Line 19
and manifold 20 connect the vaporizing tower 17 65
with the cracking chamber 11 for the introduc-
tion into the latter of the mixture of oil vapors
and non-oxidizing gases from the tower. The
unvaporized oil residue leaves the tower 17
through line 22 and is passed through a cooler 70
22a to the fuel oil tank 24 from which it may be
conveyed to the burners 2 and 2' through lines
23 and 23'. A pump 24a is inserted in line
23 to supply the fuel oil to the furnace under
sufficient pressure. 75

The cracked vapors and gases leave the crack-
ing chamber 11 through line 21, preferably lo-
cated at or near the bottom of the chamber, and
are passed through heat exchanger 14 and line
25 into the separation drum 26. The heavy 80
fraction condensed in the exchanger 14 is con-
veyed through line 14a either to the accumula-
tor 12 or to the fuel oil tank 24. A cooler 27
may be inserted in the line 25 to effect the de-
sired condensation of the products passing into 85
drum 26. Line 25 is preferably provided with
a pressure release valve 25a. In the drum, gas,
oil and water are withdrawn respectively by
lines 28, 29 and 30. Water is carried to the
sewer, the oil to storage (not shown) and the 90
gas to a system for the recovery of normally
liquid hydrocarbons.

The recovery system may be of any approved
type. In the drawing, an absorption type is
shown for the purpose of illustration. The gas 95
and uncondensed vapors are conducted to the
base of scrubbing tower 33. Absorption liquid
such as straw oil is introduced at the top by
line 34 and while flowing countercurrent to the
gases absorbs the vapors of the normally liquid 100
hydrocarbons from the latter. The oil is with-
drawn, preheated in exchanger 35 and fed into
a suitable tower stripping still 36. The distillate
is removed by vapor line 37 to condenser 38 and
storage (not shown) and the liquid after pass- 105
ing through exchanger 35, and a cooler 39, is
returned to tower 33 by pipe 34. The stripped
gas leaves through line 40. A part of the gas
may be compressed by compressor 41 and after
admixture with fresh hydrocarbon gas from line 110

42 may be returned to the burners 2 and 2' by lines 43 and 43' respectively.

In the operation of my process a fuel such as natural gas, refinery gas, fuel oil, etc. is burned preferably under a gauge pressure of 5 to 50 lbs. per square inch, although pressure may be considerably higher. The fuel is burned with as little excess air as conveniently possible whereby combustion temperatures in the neighborhood of 2500-3000° F. are obtained. The highly heated gas is then admixed with a large amount of steam under pressure and at a much lower temperature so as to reduce the gas temperature to approximately 1400-1600° F., say 10 1500° F. in the manifold 10 and to 1000-1200° F. at the outlet end of line 8'. When the line 8' is supplied by the bypass line 8a additional steam is supplied from line 9'. The cracking stock such as a topped asphalt base crude, low 15 grade fuel oil, etc. is pumped from the accumulator through the heat exchanger 14 into the vaporizing tower 17 into which it is discharged 20 through spray head 16. The liquid hydrocarbons come into intimate contact with the hot non- 25 oxidizing gases and vaporize to a great extent. The temperature in the vaporizing zone is at approximately 750-850° F. The unvaporized asphaltic residue is passed through line 22 and cooler 22a to the fuel oil tank 24. A certain 30 amount of cracking may also take place in the vaporizing tower 16, however, the bulk of the hydrocarbon vapor remains uncracked, leaves the tower 16, in admixture with the gases, through line 19 and is then introduced into the 35 cracking chamber by manifold 20. In cracking chamber 11 the hydrocarbon vapors become thoroughly admixed with the hot non-oxidizing gases which enter by the manifold 10. The temperature in the cracking chamber is high, 40 about 900-1400° F. and consequently the hydrocarbon vapors undergo a very thorough cracking.

Pressure may be maintained on the furnaces, vaporizing tower and cracking chamber of for 45 example a gauge pressure from 5-50 lbs. per square inch. If desired, the apparatus can be operated at atmospheric pressure and some of the advantages of the invention will be retained. The gases and cracked vapors leaving 50 together through line 21 are cooled in the heat exchanger 14 and finally condensed in cooler 27, after which the various products gas, oil, water are separated as it is easily understood from 55 the drawing and the description of the apparatus. The heavy product condensed in heat exchanger 14 may be returned to the cracking process. The residual gases are treated for the removal of light oils and the oily products from drum 26 may be distilled to separate the 60

low boiling from the high boiling fractions. The latter may be returned to the cracking process.

The operating pressure is either released at the valve 25a, or the separation drum and the gas absorber may also be held under pressure. 80

The following example will illustrate the operation and the yields obtained.

A residual fuel oil obtained as tar in a liquid phase cracking process and having a gravity of 8° A. P. I. was submitted to cracking by the present process under a gauge pressure of 5 lbs./sq. in. The temperatures were 850° F. in the vaporizing tower and 1200° F. in the cracking chamber. There were obtained:

15% non-condensed gas 90

74.8% oil (synthetic crude)

10% heavy fraction from the heat exchanger

14

The synthetic crude gave on fractionation:

25% gasoline with 400° F. end point of distillation. 95

50% gas oil

25% residual fuel bottoms

I claim:

1. An improved process for cracking hydrocarbon oil by direct contact with hot gases which comprises generating a hot non-oxidizing gas at a high temperature in a gas generating zone, cooling the gas to an appropriate temperature by admixing steam therewith to obtain a hot non-oxidizing gas-steam mixture, introducing the hydrocarbon oil together with part of the hot non-oxidizing gas-steam mixture into a separate vaporizing zone to effect the vaporization of a substantial part of the oil, separately removing the unvaporized oil and the mixture of vaporized oil and non-oxidizing gas, passing the last mentioned mixture into a separate cracking zone, introducing the rest of said hot non-oxidizing gas-steam mixture into the cracking zone at a temperature sufficient to effect a substantial cracking of the vaporized hydrocarbon oil, maintaining a substantially uniform temperature throughout the cracking zone, removing the cracked products from the cracking zone and separating low boiling oil from said removed cracked products. 105

2. The process according to claim 1 in which the cracking zone is maintained under a gas pressure of from 5-50 pounds per square inch. 110

3. The process according to claim 1 in which a temperature of from 750-850° F. is maintained in the vaporizing zone. 115

4. The process according to claim 1 in which the mixture of vaporized oil and non-oxidizing gas is passed into the cracking zone at a plurality of widely spaced points. 120
